UNITED STATES PATENT OFFICE.

HARRY WACHENHEIMER, OF PROVIDENCE, AND ERNEST L. DAVIS, OF CRANSTON, RHODE ISLAND, ASSIGNEES TO WACHENHEIMER BROS., OF PROVIDENCE, RHODE ISLAND, A FIRM COMPOSED OF JACOB WACHENHEIMER AND SAMUEL WACHENHEIMER, BOTH OF NEW YORK, N. Y., AND HARRY WACHENHEIMER, OF PROVIDENCE, RHODE ISLAND.

CHAIN.

1,219,683.

Specification of Letters Patent. Patented Mar. 20, 1917.

Application filed February 8, 1916. Serial No. 77,082.

To all whom it may concern:

Be it known that we, HARRY WACHENHEIMER, of Providence, county of Providence, and State of Rhode Island, and ERNEST L. DAVIS, of Cranston, county of Providence, and State of Rhode Island, have invented certain new and useful Improvements in Chains; and we do hereby declare the following specification, taken in connection with the accompanying drawings, forming a part of the same, to be a full, clear, and exact description thereof.

The invention relates primarily to chains, but is especially adapted for use in the jewelry art in the construction of bracelets, rings, necklaces and the like.

The principal object of the invention is to provide a novel construction of chain in which the use of solder is obviated and which is capable of great longitudinal flexibility.

Another object of the invention is to produce a chain which is simple in construction and inexpensive to manufacture, and which is composed of a series of links which are so constructed as to enable them to be easily and quickly attached to or removed from the chain.

To these ends the invention consists of the novel construction and arrangement of parts hereinafter described and more particularly set forth in the claims. In describing the invention in detail reference will be made to the accompanying drawings, in which—

Figure 1 is a top plan view of a portion 35 of our improved chain.

Fig. 2 is a side elevation.

Fig. 3 is a bottom elevation.

Fig. 4 is an enlarged longitudinal central section showing the longitudinal flexibility 40 of the links.

Figs. 5, 6, 7 and 8 are detail views of the block-links.

Figs. 9 and 10 are detail views of the connecting links.

Referring to the drawings, our improved chain comprises a plurality of block-links 1, each of which consists of a substantially rectangular solid body portion and a series of connecting links 2, each of which consists of a substantially rectangular flat body portion provided with a central opening therein.

Each of the block-links 1 is provided at each end upon the bottom with a transverse channel 3 and with a flat rectangular arm 4 formed integral with the end of the body 5 portion.

Said block-link 1 is preferably stamped out of sheet-metal with the arms 4 extending laterally from the end portions as shown in Fig. 5. Said arms 4 are then bent downwardly so as to be flush with the ends of the body portion as shown in Figs. 6 and 7.

The connecting links 2 are provided with two flat end portions 5 connected together at their upper portions by two bars 6 which 65 form a central opening 7 in said link, as shown in Figs. 9 and 10.

In assembling the links, the arms 4 of two adjacent block-links are passed through the central opening 7 in one of the connecting links and each of said arms is bent around one of the rods 6 so that the free end of each arm will rest against the inner edge of the channel 3 in its respective link.

The end portions of the connecting links 2 are made to correspond in thickness with the depth of the channels 3, so that when the links are assembled, said end portions will be flush with the bottom of the block-links, as shown in Fig. 2. 80

By reason of the fact that the bars 6 extend from the upper portion of the ends of the connecting links, the arms 4 when bent around said rods will be flush with the bottom of the body portion of the block-links, 85 as shown in Fig. 4.

With the above construction it will be seen that while the block-links will be held close together when the chain lies flat, as shown in Figs. 1 and 2, yet said links are 90 capable of considerable movement with relation to each other, as shown in Fig. 4, thereby giving to the chain an extreme amount of flexibility, which is very desirable in this class of chains. It is preferred 95 to provide the block-links with a central conical cavity to receive a gem or other ornamentation, which gives to the completed chain an ornamental appearance.

What we claim as our invention and desire to secure by Letters Patent is:

1. An article of the character described,

- comprising a plurality of solid block-links and a plurality of connecting links pivotally joining said block-links.
2. An article of the character described, comprising a plurality of solid block-links and a plurality of rectangular connecting-links pivotally joining said block-links adjacent the bottom thereof.
3. An article of the character described, comprising a plurality of block-links and a plurality of connecting links, each of said block-links being provided at each end with an arm embracing an adjacent connecting link.
- 15 4. An article of the character described, comprising a plurality of block-links and a plurality of connecting-links, each of said block-links being provided at each end with an arm flush with said end and each of said connecting links being provided with means embraced by the arms on two adjacent block-links.
5. An article of the character described, comprising a plurality of block-links and a plurality of connecting links, each of said block-links being provided at each end with a transverse channel and a bendable arm, and each of said connecting links being provided with two bars, one of said bars engaging the transverse channel and being embraced by the bendable arm at one end of one of said block-links, and the other bar
- engaging the transverse channel and being embraced by the bendable arm of the next adjacent block-link.
6. An article of the character described, comprising a plurality of block-links, each consisting of a body, a transverse channel upon the bottom adjacent each end and a downwardly and rearwardly extending arm flush with each end of said body portion and having their free ends engaging the inner edge of said transverse channel and flush with the bottom of the body, and a plurality of connecting links, each consisting of two flat end portions and two integral connecting bars spaced apart from each other and located above the bottom of said end portions, one of said bars being loosely mounted in the transverse channel of one of said block-links and the other of said bars being loosely mounted in the transverse channel of the next adjacent block-link.
7. A chain link consisting of a body provided at each end upon the bottom with a transverse channel and an arm flush with each end and bent around each of said channels.

HARRY WACHENHEIMER.
ERNEST L. DAVIS.
